(57) **CLAIM**

The ornamental design for a case, as shown and described.

DESCRIPTION

FIG. 1 is a top, front, and left side perspective elevational view of a case, shown in the closed condition, showing my new design;

FIG. 2 is a left side elevational view thereof, where the right side elevational view is a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a top, front, and left side perspective elevational view thereof, shown in the open condition;

FIG. 8 is a left side elevational view thereof;

FIG. 9 is a front elevational view thereof, shown in the open and flat condition;

FIG. 10 is a rear elevational view thereof; and,

FIG. 11 is a top, rear, and right side perspective view thereof.
